UNITED STATES PATENT OFFICE

102,465

DESIGN FOR AN ADVERTISING SIGN

Ranch S. Kimball, Salt Lake City, Utah

Application May 25, 1936, Serial No. 62,816

Term of patent 14 years

To all whom it may concern:

Be it known that Ranch S. Kimball, a citizen of the United States, residing at Salt Lake City, in the county of Salt Lake and the State of Utah, has invented a new, original, and ornamental Design for Advertising Signs, of which the following is a specification, reference being had to the accompanying drawing, forming a part of this application.

The figure is a perspective view of an advertising sign, showing my design.

I claim:

The ornamental design for an advertising sign, as shown.

RANCH S. KIMBALL.
